[57] CLAIM

The ornamental design for a vehicle tire, as shown and
described.

DESCRIPTION

FIG. 1 is a right side elevation view of a vehicle tire
showing the design;

FIG. 2 is a front elevation view thereof; and

FIG. 3 is a perspective view thereof, it being under-
stood that the tread pattern is repeated uniformly
throughout the circumference of the tire, the opposite
side being substantially the same as that shown.*FIG. 1*

FIG. 2

FIG. 3
